(57) **CLAIM**

The ornamental design for a portion of a handset, as shown and described.

DESCRIPTION

FIG. 1 is a front view of a portion of a handset showing our new design;

FIG. 2 is a perspective view thereof;

FIG. 3 is a top view thereof; and,

FIG. 4 is a right side view thereof.

The uneven broken line showing of the remainder of the handset is for illustrative purposes only and forms no part of the claimed design.

1 Claim, 3 Drawing Sheets

FIG. 1

FIG. 2

FIG. 3

FIG. 4

UNITED STATES PATENT AND TRADEMARK OFFICE
CERTIFICATE OF CORRECTION

PATENT NO. : Des. 501,470 S
DATED : February 1, 2005
INVENTOR(S) : William Yau et al.

Page 1 of 1

It is certified that error appears in the above-identified patent and that said Letters Patent is hereby corrected as shown below:

Title page.

Item [75], Inventors, "Todd Woods" has been replaced with -- **Todd Wood** --.

Signed and Sealed this

Nineteenth Day of July, 2005

JON W. DUDAS
Director of the United States Patent and Trademark Office
